EXPANSIBLE MANDREL

Giuseppe Cozzo, Yonkers, N. Y., assignor to Hydropress, Incorporated, New York, N. Y., a corporation of Delaware

Application April 3, 1951, Serial No. 219,021

12 Claims. (Cl. 242—72)

1

This invention relates to coil handling apparatus and particularly to an arrangement useful in conjunction with uncoiling strip material.

In handling sheet material, it frequently is necessary to coil the same and then to pay off the coiled material to a subsequent apparatus which operates upon the material. In handling sheet soft metals, such as aluminum or brass, extreme care must be taken so as not to damage the same. When the coils are held between end flanges, the flanges tend to damage the edges of the strip. Also, it is frequently necessary to handle coils having a wide range of inside diameters so that the coil handling device should be able to accommodate the various coils. When the device is used to pay off material to succeeding apparatus, it is desirable to properly align the coiled material with the apparatus and in some instances to control the tension on the material as it is uncoiled.

One of the objects of the present invention is to provide a coil handling arrangement which will handle the material without damaging the same.

Another of the objects of the invention is to provide a pay-off coil handling mechanism wherein the coil being handled can be axially adjusted and wherein the tension on the material as it is uncoiled can be controlled.

In one aspect of the invention, a rotatable means or block is mounted in bearings, said rotatable means having coil holding means or fingers movable in a direction which is transverse to the axis of the rotatable means. The fingers can have projections supported on the rotatable means, said projections having rack teeth or similar operating means thereon. Interiorly of the rotatable means there is a coil holding means operating mechanism or sleeve having teeth thereon engageable with said rack teeth on the projections, said sleeve being mounted within said rotatable means so as to be turnable relative thereto. An operating member movable longitudinally relative to said sleeve or toothed cylinder can be provided, there being a threaded portion between the longitudinally movable operating member and the sleeve so that as the longitudinally movable member is moved relative thereto, the sleeve will be rotated by such movement. The threads should have a pitch sufficiently coarse so as to permit said relative movement of the operating member and sleeve. The longitudinally movable member preferably is operated by a hy-

2

draulic piston mounted on the rotatable means. The rotatable means may have a yoke or similar mechanism operatively connected thereto for moving the entire assembly relative to the bearings in which it is supported. This makes it possible to axially position a coil of strip material held by the fingers of the rotatable means. Also, there may be a brake drum mechanism connected with the rotatable means for the purpose of controlling the angular velocity of the coil as strip is fed therefrom.

These and other advantages, objects and features of the invention will become apparent from the following description and drawings.

15 In the drawings:

Fig. 1 is a fragmentary view of a portion of the coil handling apparatus of the invention.

Fig. 2 is a sectional view of the arrangement shown in Fig. 1 taken generally along the center line.

Fig. 3 is a schematic perspective view of the coil engaging means of Figs. 1 and 2.

20 Fig. 4 is a fragmentary side view of a portion of the frame means and mechanism supporting the pay-off coil handling arrangement of the preceding figures.

Fig. 5 is a fragmentary end view looking from the left of Fig. 4.

25 As previously mentioned, material such as soft metal strip and the like frequently must be fed from a coiled form to a succeeding operation. A rotatable supporting means or block, indicated generally by numeral 10, (Figs. 1, 2), may have an end 11 thereof arranged to hold and to guide the coil holding means or fingers 12 which are movable inwardly and outwardly relative to the longitudinal axis of the rotatable means 10. Rotatable means 10 may have an enlarged cylindrical portion 13 (Figs. 1, 2, 4) held in main frame members 14 and 15. Fingers 12 preferably extend longitudinally along the finger holding portion 11 of rotatable means 10, there being four fingers or holding means in the illustrated embodiment.

30 40 45 50 55 Each of the fingers 12 has a transverse guide member or projection 16 held in place on the portion 11 of rotatable member 10 by cover plates 17 (Figs. 1, 2), said cover plates being fastened by bolts 18 to the portion 11 of rotatable means 10. The transverse projections 16 may have rack teeth 19 (Fig. 2, Fig. 3) thereon for the purpose which will be described hereafter. Located interiorly of the finger holder portion 11 of rotatable means 10 is a finger operating sleeve or drum 21 mounted in bearings

22, 23 within the portion 11 so as to be rotatable relative to the portion 11. Sleeve 21 is held from longitudinal movement relative to the rotatable means 10. The sleeve has teeth 19' on the exterior thereof engageable with rack teeth 19.

A longitudinally movable sleeve operating member 24 has a splined portion 25 slidably engageable with guide member 26 mounted in the enlarged portion 13 of rotatable member 10. Thus, the longitudinally movable operating member 24 is not rotatable relative to rotatable member 10 as it is moved longitudinally thereon. A lubricating groove 26' may be provided.

Hydraulic piston 21 can be located in cylinder 28 within portion 13, said cylinder having fluid connection 29 for admitting fluid pressure thereto. The fluid pressure may be air, liquid or the like.

Longitudinally movable sleeve operating member 24 can have long pitch threads 30 which are slidable in the threaded portion 31 of the finger operating means or sleeve 21. Spring-pressed plunger 32 is normally urged to the left (Fig. 2) by spring 33, said spring-pressed plunger normally urging the longitudinally movable operating member 24 to the left. Spring-pressed plunger 32 can be guided by guide member 34 attached to cover 35.

Normally the parts are arranged so that when operating member 24 is in the position illustrated in Fig. 2, the coil holding fingers will be in retracted position. As the operating member 24 is moved to the right (Fig. 2), finger operating sleeve 21 will be rotated and the teeth thereon will engage the rack teeth on projections 16 so as to move the coil holding fingers into the desired extended position to engage the interior of a coil, one of these positions being shown by the dot-dash lines (Fig. 1). The fragmentary perspective view of Fig. 3 also shows the fingers in an extended position. In Fig. 3, cover plates 17 and other parts have been omitted for clarity in depicting the relative arrangement of the coil supporting fingers, four fingers being shown. It is to be understood, however, that various numbers of fingers can be used as desired. The interior diameter of the coil involved can vary widely with the arrangement just described.

Frame 36 (Fig. 4) is provided with supporting members 14 and 15 for carrying rotatable member 10. Mounted on said frame is a means for longitudinally adjusting the rotatable assembly mounted on rotatable member 10 relative to the frame 36 so as to align the coil as it is being payed-off. Lever 37 is pivoted at 38 to the frame 36 and may have a yoke arrangement 39 fastened by bolts 40 (Figs. 2, 4) to rotatable member 10 through cap 48. Cap 48 is carried by roller bearing 49 on rotatable member 10. Coil aligning hand wheel 41 (Figs. 4, 5) is connected with screw threaded member 42 which engages nut 43, nut 43 being fastened to the upper end of axial adjusting lever 37. When it is desired to axially adjust the rotatable assembly carried by rotatable means 10, hand wheel 41 may be suitably moved so as to axially move a coil supported thereby and thus align the coil with the apparatus being fed by the device.

In order to control pay-off speed or the tension in the strip being uncoiled, brake drum 44 (Figs. 1, 2, 4) can be keyed to the enlarged portion 13 of rotatable member 10. Brake band elements 45 can be pivoted at 46 to the frame and brake

operating hand wheel 47 connected to rod 48A which is suitably threaded. The threaded rod 48A is connected with threaded elements at the upper ends of the brake bands 45 so that upon rotation of the hand wheel 47, the brake members 45 can be moved toward and away from each other and the brake drum 44.

It should be evident that details of construction can be varied without departing from the spirit of the invention except as set forth in the appended claims.

What is claimed is:

1. In a strip material coil handling apparatus, the combination including rotatable means, inwardly and outwardly movable coil holding means mounted on said rotatable means, coil holding means operating mechanism rotatable relative to said rotatable means and connected thereto for moving said coil holding means inwardly and outwardly, and a single longitudinally movable operating member connected to said operating mechanism and adapted to rotate the same as said operating member is moved longitudinally relative thereto and to said rotatable means, so as to move said coil holding means into and out of coil holding position.

2. In a strip material coil handling apparatus, the combination including rotatable means, inwardly and outwardly movable coil holding means mounted on said rotatable means, coil holding means operating mechanism rotatably carried by said rotatable means, means holding said operating mechanism longitudinally fixed relative to said rotatable means, a longitudinally movable operating member screw-threadedly connected with said coil holding means operating mechanism and adapted to rotate the same relative to said rotatable means upon longitudinal movement relative to said operating mechanism, and means for moving said longitudinally movable operating member longitudinally relative to said operating mechanism and said rotatable means.

3. In a strip material coil holding apparatus, the combination including a rotatable member carried in a main frame, coil engaging finger means mounted on said rotatable member and movable transversely relative to the axis of said rotatable member, said finger means having rack teeth thereon, a sleeve carried by said rotatable member and rotatable relative thereto, said sleeve having gear teeth thereon engageable with the rack teeth on said finger means for moving the finger means in and out as the sleeve is rotated, means holding said sleeve from longitudinal movement relative to said rotatable member and an axially movable sleeve rotating means connected to said sleeve and movable longitudinally relative thereto for rotating the same to move the coil holding finger means inwardly and outwardly.

4. In a strip material coil handling apparatus, the combination including rotatable means, inwardly and outwardly movable coil holding means mounted on said rotatable means, said means having operating teeth thereon, coil holding means operating mechanism rotatably carried by said rotatable means, said mechanism having operating teeth engageable with the teeth on said coil holding means, means holding said operating mechanism from longitudinal movement relative to said rotatable means, a longitudinally movable operating member screw-threadedly connected with said coil holding means operating mechanism and adapted to rotate the same relative to said rotatable means upon longitudinal move-

ment relative to said operating mechanism and said rotatable means, and means for moving said longitudinally movable operating member.

5. In a strip material coil holding apparatus, the combination including a rotatable member carried in a main frame, coil engaging finger means mounted on said rotatable member and movable transversely relative to the axis of said rotatable member, said finger means having rack teeth thereon, a sleeve carried by said rotatable member and rotatable relative thereto, said sleeve having gear teeth thereon engageable with the rack teeth on said finger means for moving the finger means in and out as the sleeve is rotated, means holding said sleeve from longitudinal movement relative to said rotatable member, and an axially movable sleeve rotating means screw-threadedly connected to said sleeve by a long pitch thread for rotating the same to move the coil holding finger means inwardly and outwardly upon relative longitudinal movement therebetween.

6. In a strip material coil handling apparatus, the combination including a rotatable means, inwardly and outwardly movable coil holding finger means mounted on said rotatable means having gear teeth thereon, coil holding means operating mechanism rotatable relative to said rotatable means and connected to the gear teeth of said finger means for moving said coil holding finger means inwardly and outwardly, means holding said operating mechanism from longitudinal movement relative to said rotatable means, a longitudinally movable operating member connected to said operating mechanism and adapted to rotate the same as said operating member is moved longitudinally relative thereto, bearing means slidably holding said rotatable means, and means connected with said rotatable means for axially moving the same in said bearing means, so as to adjust the position of an axial coil held by said coil holding means.

7. In a strip material coil handling apparatus, the combination including rotatable means, inwardly and outwardly movable coil holding finger means carried by said rotatable means, said finger means having gear teeth thereon and being movable transversely relative to the axis of the rotatable member, coil holding means operating mechanism carried by said rotatable means and turnable relative thereto, gear teeth on said operating mechanism engageable with the gear teeth on said finger means, means holding said operating mechanism from longitudinal movement relative to said rotatable means, longitudinally movable operating means connected to said operating mechanism and adapted to rotate the same relative to said operating mechanism upon relative longitudinal movement therebetween, bearing means carrying said rotatable means, adjustable means connected to said rotatable means moving the same axially in said bearing means so as to adjust the position of a coil held thereby, and controllable brake mechanism connected to said rotatable means for controlling the speed thereof.

8. In a strip material coil handling apparatus, the combination including a rotatable means, inwardly and outwardly movable coil holding finger means mounted on said rotatable means and having gear teeth, coil holding means operating mechanism rotatable relative to said rotatable means and connected to said finger means, gear teeth for moving said coil holding finger means inwardly and outwardly, means holding said op-

erating mechanism in said rotatable means from longitudinal movement relative to said rotatable means, a longitudinally movable operating member screw-threadedly connected to said operating mechanism with a coarse pitch thread and adapted to rotate the same as said operating member is moved longitudinally relative thereto, bearing means supporting said rotatable means, and means connected with said rotatable means for axially moving the same in said bearing means, so as to adjust the position axially of a coil held by said coil holding means.

9. In a strip material coil pay-off apparatus, the combination including a frame, a rotatable means journaled in said frame, inwardly and outwardly movable coil holding finger means mounted on said rotatable means, said finger means having teeth thereon, a sleeve carried in said rotatable means and having teeth thereon engageable with the teeth of said finger means, means preventing axial movement of said sleeve relative to said rotatable means, a longitudinally movable operating member screw-threadedly engaged with said sleeve and carried by said rotatable means, and a fluid motor carried by said rotatable means connected to said longitudinally movable operating member for moving said operating member relative to said sleeve and rotatable means so as to cause rotation of said sleeve relative to said rotatable means.

10. In a strip material coil handling device, the combination including a frame, a rotatable means journaled in bearing means in said frame, inwardly and outwardly movable coil holding finger means having projecting means mounted on said rotatable means, said projecting means having teeth thereon, a sleeve-like member carried in said rotatable means and having teeth on the exterior thereof engageable with the teeth of said finger means projecting means, means preventing axial movement of said sleeve relative to said rotatable means, longitudinally movable operating means screw-threadedly engaged with said sleeve, a fluid motor carried by said rotatable means connected to said longitudinally movable operating member for moving the same relative thereto, and means mounted on said frame connected with said rotatable means for adjustably moving said rotatable means axially in said bearing means relative to said frame.

11. In a strip material coil handling device, the combination including a frame, a rotatable means journaled in bearing means in said frame, inwardly and outwardly movable coil holding finger means having projecting means mounted on said rotatable means, said projecting means having teeth thereon, a sleeve-like member carried in said rotatable means and having teeth on the exterior thereof engageable with the teeth of said finger means projecting means, means preventing axial movement of said sleeve relative to said rotatable means, longitudinally movable operating means screw-threadedly engaged with said sleeve, a fluid motor carried by said rotatable means connected to said longitudinally movable operating member for moving the same relative thereto, means mounted on said frame connected with said rotatable means for adjustably moving said rotatable means axially relative to said frame in said bearing means, and brake mechanism mounted on said rotatable means adjustable to regulate the tension on strip material being payed off from a coil mounted on said coil holding finger means.

12. In a strip material coil pay-off apparatus,

the combination including a frame, a rotatable means journalled in said frame and having a portion overhanging said frame, a plurality of inwardly and outwardly movable coil holding finger means mounted on said portion overhanging said frame, said finger means having teeth thereon, a sleeve rotatably mounted in said rotatable means, said sleeve having teeth on the exterior thereof engageable with the teeth of said finger means, means preventing axial movement of said sleeve relative to said rotatable means, a longitudinally movable operating member having relatively coarse screw-threads on the exterior thereof engageable with screw-threads on the interior of said sleeve, a fluid operated piston mounted on said rotatable means and connected to said longitudinally movable operated member for moving the same in one direction, and re-

silent means for moving said operating member in the opposite direction, longitudinal movement of said operating member relative to said sleeve causing rotation of said sleeve relative to said portion overhanging said frame.

GIUSEPPE COZZO.
